UNITED STATES PATENT OFFICE.

PETER S. KINSEY, OF NEWARK, ASSIGNOR TO THE AUSTRALIAN KNITTING COMPANY, OF PATERSON, NEW JERSEY.

DESIGN FOR A KNITTED FABRIC.

SPECIFICATION forming part of Design No. 19,647, dated February 11, 1890.

Application filed January 16, 1890. Serial No. 337,117. Term of patent 7 years.

To all whom it may concern:

Be it known that I, PETER S. KINSEY, of Newark, in the county of Essex and State of New Jersey, have invented and produced a new and original Design for Knitted Fabrics, of which the following is a specification.

The accompanying drawing illustrates a design embodying my invention, the design being shown in the black portions of the figure.

The design consists, essentially, of a row of diamond-shaped figures A, joined together by substantially straight lines a. Arranged upon one side of said diamond-shaped figures is a substantially zigzag line B, upon the outer edge of which is a straight line C.

Upon the other side of said diamond-shaped figures is a zigzag line D, upon the outer edge of which is a straight line E. I have shown outside the straight line E another zigzag line F, the zigzags of which are shown arranged so that the zigzags D and F will constitute a substantially continuous S-shaped line extending about the straight line E.

What I claim as my design is—
The design for knitted fabrics, substantially as herein shown and set forth.

PETER S. KINSEY.
